UNITED STATES PATENT OFFICE.

DANIEL D. SWEM, OF BRIDGEPORT, CONNECTICUT, ASSIGNOR TO THE ARTISTIC BRONZE COMPANY, OF BRIDGEPORT, CONNECTICUT, A CORPORATION OF CONNECTICUT.

BRACKET HINGE.

Application filed February 3, 1926. Serial No. 85,662.

This invention relates to door hinges and especially to hinges for refrigerator doors, although it is, of course, not limited to use with this type of door. It is an object of 5 the invention to provide a simple hinge which will tend to hold the door in closed position, which will limit the opening movement of the door, and which will be so constructed and arranged as to increase the 10 force tending to close the door as the door is moved toward open position, so that when used with a door mounted to swing in a vertical plane the force tending to close the door will increase with the effective 15 weight of the door as it is swung downwardly to the open position, thus preventing jar or sudden shock in the opening of the door, with the resultant excessive strains on the hinge and the securing means therefor. 20 With the foregoing and other objects in view, I have devised the construction illustrated in the accompanying drawing forming a part of this specification, similar reference characters being employed throughout 25 the various figures to indicate corresponding elements. In this drawing,

Fig. 1 is a front elevation of a hinge shown as applied to a refrigerator door mounted to swing downwardly about an axis 30 in a horizontal plane.

Fig. 2 is a side elevation thereof showing the door in closed position.

Fig. 3 is an end elevation looking toward the bottom of Fig. 1, and

Fig. 4 is a side elevation showing the door in open position.

In the drawing I have shown the hinge as applied to a door in the rear wall of a refrigerating counter or showcase. It is usual 40 in this type of installation to have the rear wall of this case, indicated at 10, inclined as shown in Figs. 2 and 4 at an angle of about fifteen degrees to the vertical, and the door (D) is mounted to swing in a vertical 45 plane about a horizontal axis with the upper edge free so that the door swings outwardly and downwardly on hinges mounted at the lower edge thereof. I wish it to be understood, however, that this hinge is not 50 limited to use with doors mounted in this manner, but is also adapted for doors mounted to swing in a horizontal plane about a vertical axis. The hinge comprises a butt 11 secured to the rear wall by suitable screws 55 12, and a strap 13 secured to the door as

by suitable screws 14 and pivotally connected to the butt. In the present instance the butt is provided with spaced ears 15 extending at right angles to the body of the butt between which the strap is pivoted by 60 means of a pin 16.

A bar spring 17 is rigidly secured to the strap, preferably adjacent the upper end thereof, by any suitable means such as rivets 18. This spring may comprise one or more 65 flat strips of spring metal, there being two superposed strips in the spring shown in the drawing. Also pivoted to the butt, preferably between the ears 15, is a member 19 which I term a yoke. In the present construction it is shown as a bar of metal bent to substantially U-shape with its opposite free ends 20 pivoted in the ears of the butt at a point below the pivot 16 for the strap or on the opposite side of this pivot from the 70 strap when the door is in the closed position, and it is spaced from this pivot. The intermediate or body portion of the door is pivoted to the free end of the spring 17 as by means of a loop 21 wrapped around the 75 yoke. The spring is preferably of such a length that when the door is in the closed position the yoke is inclined outwardly and upwardly, as indicated in Fig. 2.

It will be apparent from an inspection of Fig. 2 that as the spring 17 is under tension and its free end tends to move inwardly toward the strap, the tension of this spring tends to close the door and to hold it in the closed position. It will also be apparent 85 that as the free end of the spring and the yoke swing about the pivoted ends 20 of the yoke in the butt, as indicated by the arc 22, when the door is opened and as the pivot point 20 is below the pivot 16 about which 90 the strap swings, the pivot 21 between the spring and the yoke during this movement will swing farther and farther away from the pivot 16, thus increasing the tension on the spring as the door is swung toward the 95 open position. Thus, although the effective weight of the door increases as the free upper edge thereof is swung downwardly and outwardly about the pivot 16, the tension of the spring is substantially correspondingly increased to compensate for this 100 increase in the effective weight of the door, and the maximum tension will be placed on the spring when the pivot 16 for the strap, the pivot 20 for the yoke to the butt, and 105 110

the pivotal connection 21 between the yoke and the spring are substantially in a straight line. The spring is so mounted and proportioned, as is also the yoke, to bring about this condition when the door is in the substantially extreme open position or just before it reaches this position which is substantially horizontal as shown in Fig. 4. Thus the greatest tension is on the spring and it exerts its greatest force to close the door when the effective weight of the door is at the maximum. It is, however, preferred not to make the spring of sufficient tension to swing the door to the closed position from this extreme open position, but to merely compensate for the weight of the door so that the door will be suspended by the spring and it will not swing open with a jar or sudden shock with its consequent excessive strain on the parts of the hinge and the securing means therefor. It is, however, desirable that when the door approaches the upright position the spring will have sufficient tension to swing it to the closed position to prevent the door being inadvertently left open a short distance in the closing operation. It will, of course, be understood, that, if found desirable the spring may be made of sufficient tension to close the door from the open position.

Normally when the door is wide open the weight is on the springs of the hinges as the free end of the spring in this position engages the butt of the hinge as indicated in Fig. 4. In order to prevent breaking of the springs by the placing of an excessive weight on the door I have provided a rigid stop means. This is shown in the drawing as a stop lug 23 on the butt and extending outwardly therefrom and having a free upper edge 24 located just below the lower surface of the strap when the door is in its normal extreme open position to provide a slight clearance. This will insure that the door in this position is normally held by the springs. Should, however, an excessive weight be placed on the door the springs will bow upwardly as indicated in dotted lines in Fig. 4 and allow the door to move downwardly slightly to the dotted line position until the strap rests on the upper edge of this stop lug. This will provide a rigid stop or support preventing any further movement and also preventing breaking of the spring. It will, of course, be apparent that this stop lug may be reversed and mounted on the strap so as to engage the butt with the same effect.

Although I have shown a single hinge for the door it will, of course, be obvious that normally two or more hinges will be used for a door. If the hinges are used on doors swinging in a horizontal plane about a vertical axis the springs in this case are not called upon to support the weight of the

door so that they will swing the door toward closed position. However, if the pivot 16 for the strap, the pivot 20 for the yoke and the pivotal connection 21 between the yoke and the spring are so arranged that they are in a straight line when the door is open, or so that the connection 21 passes slightly beyond the line joining the centers of the pivots 16 and 20, this spring will retain the door in the open position, but after a slight movement toward closed position the spring will swing it the rest of the way to closed position.

It will be apparent from the foregoing description that the hinge is very simple in construction, and that the supporting tension of the spring for the door gradually increases as the effective weight of the door increases, to compensate therefor, as the door is swung outwardly and downwardly toward the open position. Also that the spring forms the stop to normally limit the open movement of the door so that this gradual increase of tension together with engagement of the spring with the butt at the end of the opening movement prevents jar or sudden shock as the door reaches the extreme open position.

Having thus set forth the nature of my invention, what I claim is:

1. A door hinge comprising a butt, a strap pivoted to the butt, a yoke pivoted to the butt on the opposite side of the strap pivot from the strap when the door is closed, and a laterally yieldable spring rigidly secured to the strap and pivoted at its free end to the yoke at a distance from its connection to the butt.

2. A door hinge comprising a butt, a strap pivoted to the butt, a bar spring secured to the strap, a yoke pivoted to the spring and the butt and arranged to force the free end of the spring outwardly away from the strap as the door is moved toward open position.

3. A door hinge comprising a butt, a strap pivoted to the butt, a yoke pivoted to the butt on the opposite side of the strap pivot from the strap when the door is closed, and a bar spring rigidly secured to the strap and pivoted at its free end to the yoke, the length of the spring being such that the yoke is inclined toward the strap when the door is in the closed position.

4. A door hinge comprising a butt having spaced ears, a strap pivoted to said ears, a substantially U-shaped yoke pivoted at its free ends to said ears laterally of the strap pivot, and a bar spring rigidly secured to the strap and pivoted at its free end to the intermediate portion of the yoke.

5. A door hinge comprising a butt, a strap pivoted to the butt, a yoke pivoted to the butt on the opposite side of the strap pivot from the strap when the door is closed, and

a bar spring rigidly secured to the strap and pivoted at its free end to the yoke at a distance outwardly from the connection of said yoke to the butt, the free end of the spring being arranged to engage the butt to provide a stop when the door is in the extreme open position.

6. A door hinge comprising a butt, a strap pivoted to the butt, a yoke pivoted to the butt on the opposite side of the strap pivot from the strap when the door is closed, a bar spring rigidly secured to the strap and pivoted at its free end to the yoke at a distance from the connection of said yoke to the butt, the free end of the spring being

arranged to engage the butt to provide a yieldable stop for the door when in open position, and a rigid stop between the butt and strap to limit movement of the door beyond this position.

20

7. A door hinge comprising a butt, a strap pivoted to the butt, a yoke pivoted to the butt on the opposite side of the strap pivot from the strap when the door is closed, and a spring exerting a lateral pressure carried by the strap and having a pivotal connection to the yoke at a distance from its connection to the butt.

25

In testimony whereof I affix my signature
DANIEL D. SWEM.
